Primary Examiner — Susan Bennett Hattan*Assistant Examiner* — Leanne Was(74) *Attorney, Agent, or Firm* — Benjamin D. Rotman; Rosenbaum IP, P.C.(57) **CLAIM**

The ornamental design for a multifunction tool, as shown and described.

DESCRIPTION

FIG. 1 is a top perspective view of a multifunction tool in accordance with the invention;

FIG. 2 is a bottom perspective view of FIG. 1;

FIG. 3 is a top plan view of FIG. 1;

FIG. 4 is a bottom plan view of FIG. 1;

FIG. 5 is a front elevation view of FIG. 1;

FIG. 6 is a rear elevation view of FIG. 1;

FIG. 7 is a right side elevation view of FIG. 1; and,

FIG. 8 is a left side elevation view of FIG. 1.
